WILLIAM H. CURTIS

or James V. Ramsey

ATTORNEY

UNITED STATES PATENT OFFICE.

WILLIAM H. CURTIS, OF WEST BADEN, INDIANA.

PORTABLE ADJUSTABLE BATHING STRUCTURE.

Application filed January 23, 1924. Serial No. 688,071.

To all whom it may concern:

Be it known that I, WILLIAM H. CURTIS, a citizen of the United States, residing at West Baden, in the county of Orange and State of Indiana, have invented certain new and useful Improvements in Portable Adjustable Bathing Structures, of which the following is a specification.

My invention relates to portable adjustable bathing structures which are adapted to float upon the surface of a river or other body of water.

Many rivers and other bodies of water adjacent the centers of population are without suitable bathing beaches for various reasons among which are: muddy or rocky bottoms, swift and dangerous current, great depth of the water and treacherous step-offs or holes, which disadvantages render bathing unsafe or undesirable to a great majority of persons.

The object of my invention is to provide a safe and satisfactory floating portable adjustable bathing structure adapted to be placed in rivers, lakes or other bodies of water to furnish a desirable bathing place for men, women and children and which is entirely safe and sanitary, since it permits of adjustment to various depths of water and permits the flowing water to readily pass therethrough.

Another object of the invention is to provide convenient bath rooms upon pontoons suitably spaced apart and connected together and having mounted therebetween a vertically adjustable open work enclosure provided with a floor to form a safe bathing pool for persons of all ages.

My invention consists in providing and securing pontoons in spaced apart relation from each other and in mounting therebetween a vertically adjustable bathing enclosure.

My invention also consists in the construction, combination and arrangement of parts as herein set forth and claimed.

In the drawings:

Fig. 1 is a perspective view of the entire bathing structure;

Fig. 2 is an end elevation thereof;

Fig. 3 is a bottom view of Fig. 1;

Fig. 4 is a perspective view of the open work bathing enclosure;

Fig. 5 is a perspective view of the bathing enclosure supporting structure;

Fig. 6 is an inside elevation of one side of the bathing enclosure;

Fig. 7 is a vertical longitudinal section of my invention taken on a plane corresponding to line 7—7 of Fig. 2 with the bathing enclosure omitted;

Fig. 8 is a perspective view of one of the auxiliary floors; and

Fig. 9 is a central vertical section thereof.

In the embodiment of my invention, as illustrated and which shows a preferred construction, I provide a portable adjustable bathing structure 1 which is shown in its entirety in Fig. 1.

The foundation or supporting structure 70 consists of pontoons 2 and 3 extending along the respective sides of the bathing pool and secured together at each end in spaced apart relation by cross bars 4 bolted to the ends of each pontoon and cross bars 5 spaced apart 75 from cross bars 4 and fitting between the pontoons and connected thereto by means of angle irons 6 which are bolted respectively to said cross bars 5 and pontoons 2 and 3. Pontoon 2 is provided with floor 7 and pontoon 3 is provided with floor 8. Said floors 7 and 8 are connected at each end by walkways 9 and 10 mounted upon cross bars 4 and 5 at the respective ends of the structure.

A series of spaced apart vertical guides 85 11 are secured at their lower ends to the inner side of each pontoon 2 and 3 respectively and similar guides 12 are secured at their lower ends to the inner sides of cross bars 5. The upper ends of said guides 11 and 12 extend upwardly a considerable distance above the upper surface of the pontoons and are suitably secured at their tops to the arches 13' of rectangular frame 13. A metal plate 14 having notch 15 in its lower edge is mounted upon the inner lower ends of the respective guides 11 and 12. These plates are adapted to hold the sliding posts (21) in position in guides 11 and 12 and also serve to hold the sides and ends of the enclosure in upright position.

Bathing enclosure 16 comprises the under-beam structure which consists of longitudinal beam 17 and cross beams 18, 19 and 20 and vertical sliding posts 21 which posts 105 are hingedly connected to beams 17, 18, 19 and 20. Flooring 22 of the bathing enclosure 16 is preferably formed of strips slightly spaced apart and suitably secured to said beams, thereby permitting the free 110

circulation of fresh water and causing any dirt or sediment to wash away; and also providing a perfectly clean and sanitary pool at all times. The floor may be made in sections of suitable width and length for convenience in handling and when storing or shipping it. The sides 23 of said enclosure are formed of spaced apart or open work sections or panels 24 located between 5 and spaced apart from each upright post 21 and intermediate solid sections or panels 25 secured to the respective panels 24 and mounted adjacent the inner surface of said posts but slightly spaced apart therefrom. 10 The respective ends 26 are formed of spaced apart or open work sections or panels 27 connected by intermediate solid panels 28 as shown and arranged in the same manner as solid panels 25. The respective sides 15 and ends are suitably attached to the bottom by hinges 29 to provide for flexibility which permits the parts to yield slightly under pressure of the waves or current of water and the weight and movements of the 20 bathers. It also prevents binding or pinching in raising or lowering the bathing enclosure. The sides and ends, as well as the bottom being formed of suitable open work or spaced apart strips permits the water to 25 freely flow therethrough and also secures the bathers against being washed or floated out into deep water.

This bathing enclosure 16 is mounted between the pontoons 2 and 3, the several posts 25 30 35 40 45 50 55 60 65 70 75 80 85 90 95 100 105 110 115 120 125 130 135 140 145 150 155 160 165 170 175 180 10780 10785 10790 10795 10800 10805 10810 10815 10820 10825 10830 10835 10840 10845 10850 10855 10860 10865 10870 10875 10880 10885 10890 10895 10900 10905 10910 10915 10920 10925 10930 10935 10940 10945 10950 10955 10960 10965 10970 10975 10980 10985 10990

5 roof 50 of these dressing rooms may be used as a rest or recreation place for bathers and others and said roof may be provided with suitable benches 51 and chairs 52. Stairs 5 or steps 53 are provided for convenient access to the roof. A safety railing 54 is preferably provided.

10 I also preferably provide an elevated platform 55 upon pontoon 3 similar to roof 50 having stairs 56 leading thereto and being enclosed for safety by railing 57. Said platform serves to provide a shelter and to shade the flooring of said pontoon and may be used for any desired purpose.

15 Flexible diving board 58 having one end 59 fixed to elevated platform 60 has non-slipping material 61 secured to its free end for the purpose of enabling bathers to stand thereon and dive therefrom into the pool without danger of slipping. Steps 62 lead from walk-way 10 to platform 60 for convenient accessibility to the diving board.

20 Steps 63 are placed on the sides of the bathing enclosure for convenience of bathers in entering or leaving the bathing pool.

An advantage of the invention consists in means whereby the pool enclosure can be raised up so that the bottom is above or even with the bottoms of the pontoons to permit the bathing structure to be drawn up close to the bank of the river or other body of water.

25 Another advantage of my invention is that when there is a high stage of water which entirely submerges the bathing beaches, my floating bathing enclosure may be suitably anchored and used with entire safety.

30 When it is desired to move or transport the structure from one point to another upon the water, the bathing enclosure may be elevated to a position above the water so that the pontoons only will draw against the water, thereby greatly facilitating the moving of the structure from one location to another with a greatly reduced draft of power.

35 By adjusting the pool enclosure to the elevated position out of contact with the water the draft of the pontoons only in the water would be reduced to a minimum, whereby

the entire structure can be transported 50 through very shallow water, not drawing over fourteen inches in depth and thereby permit it to be transported over long distances of shallow water from one bathing point to another.

35 A further advantage of my invention is that in case any of the bathers, (who might suddenly, through weakness, cramps, heart failure or otherwise, such as inexperience in swimming) should become helpless, the bathing enclosure may be quickly raised to permit the water to run out and thereby save the bather from drowning.

40 My invention is capable of some modification without departure from its scope or spirit as defined in the claim, as for instance, fairly good results may be obtained by a permanent open work non-adjustable enclosure between the pontoons.

45 What I claim as new and desire to secure 70 by Letters Patent is:

In a portable adjustable bathing structure, a pair of pontoons spaced apart and connected together and having a plurality of vertical side and end upwardly extending 75 guides, a metal plate mounted on the inner lower end of each guide and having a notch in its lower edge, a bath enclosure supporting structure comprising horizontal beams and upright posts hinged thereto, said upright posts being mounted to be moved vertically in said guides, respectively, and said horizontal beams adapted to be moved into and out of said notches, an open-work bathing enclosure comprising alternating open-work panels and solid panels, said open-work panels being in alinement and spaced apart from each other at their ends and said solid panels being connected to said open-work panels in parallel relation therewith, 80 an open-work bottom, hinges connecting said panels to said bottom, said upright posts being disposed between the ends of said open-work panels, respectively, all combined and operating, substantially as set forth and 85 for the purposes specified.

90 WILLIAM H. CURTIS.
